TALKING MOTION PICTURE APPARATUS

Filed Jan. 22, 1927

Inventor:
Charles F. Bateholts,
by *Alexander S. Lantz*,
His Attorney.

UNITED STATES PATENT OFFICE.

CHARLES F. BATEHOLTS, OF SCHENECTADY, NEW YORK, ASSIGNOR TO GENERAL ELECTRIC COMPANY, A CORPORATION OF NEW YORK.

TALKING-MOTION-PICTURE APPARATUS.

Application filed January 22, 1927. Serial No. 162,897.

My invention relates to talking motion picture apparatus by which motion pictures and accompanying sounds are simultaneously produced and particularly to that part of the apparatus which affects the relation between the actual source of the sounds and the persons or objects shown by the pictures as producing the sounds.

In former apparatus of this character the sounds which accompany the pictures and which are intended to give one the impression as coming from the persons or objects shown in the pictures have been commonly produced by a sound producing device of some well known construction arranged at some point adjacent the screen, as for example on the floor near the bottom of the screen. With the sound device so placed a person observing the pictures frequently is conscious of the fact that the sounds do not come from the source of the sounds as shown by the pictures, particularly is this true when the source of the sound being illustrated happens to be on that portion of the screen which is furthest removed from the sound device.

An object of my invention therefore is the provision in apparatus of this character of improved means for overcoming this objection and for making the presentation more realistic.

My invention will be better understood from the following description taken in connection with the accompanying drawing, and its scope will be pointed out in the appended claim.

Referring to the drawing which illustrates in a single figure an embodiment of my invention, I have shown at 1 a screen of any suitable material upon which the motion pictures may be projected by apparatus not illustrated. Spaced behind the screen I have shown the sound producing device 2 which in the present instance is illustrated by way of example as a loud speaker whose front or sound emitting side faces the rear of the screen. I have also shown the device 2 as being enclosed by the casing 3 having an opening opposite the front of the loud

speaker. Extending between the screen and 50 the loud speaker is the tapered casing 4 which is arranged with its small end covering the opening in casing 3 and with the periphery of its outer end enclosing and spaced from the screen 1. Between the edges of the 55 screen and the periphery of the casing 4, I have shown a mask 5 forming in effect a frame for the screen and constructed of material through which the sound waves are readily transmitted. Within the outer casing 4 60 is the inner tapered casing 6 which has the peripheral edge of its large end arranged adjacent the periphery of the screen and has its small end converging to a point. A sound passage or channel is thereby provided between the walls of the inner and outer casings 6 and 4 respectively through which the sound waves are transmitted from the loud speaker to a region or zone surrounding the 65 screen. The loud speaker need not necessarily be located directly behind and at a distance from the screen but if desired may be arranged in various other positions, the casings being suitably shaped to provide a proper sound conducting passage from the 70 loud speaker to the region surrounding the screen. Under certain circumstances I may dispense with the casing 3, the sound emitting front of the loud speaker being merely arranged opposite the small end of the 75 outer casing.

What I claim as new and desire to secure by Letters Patent of the United States, is:

In talking motion picture apparatus, a 85 screen upon which motion pictures are adapted to be projected, a device for producing accompanying sounds arranged in the rear of the screen, a tapering inner enclosure extending rearwardly from the edges of the 90 screen, and a tapering outer enclosure spaced from the inner enclosure and associated at its smaller end with the sound producing device.

In witness whereof, I have hereunto set 95 my hand this 21st day of January, 1927.

CHARLES F. BATEHOLTS.
